UNITED STATES PATENT OFFICE.

STEPHEN A. MISCHANSKY, OF SYRACUSE, NEW YORK, ASSIGNOR OF THIRTY ONE-HUNDREDTHS TO STANISLAW LNISKI, OF SYRACUSE, NEW YORK.

APPARATUS FOR DEVELOPING PHOTOGRAPHIC PLATES.

1,202,405.

Specification of Letters Patent.

Patented Oct. 24, 1916.

Application filed February 17, 1915. Serial No. 8,715.

To all whom it may concern:

Be it known that I, STEPHEN A. MISCHANSKY, a subject of the Emperor of Austria-Hungary, and resident of Syracuse, in the county of Onondaga, in the State of New York, have invented new and useful Improvements in Apparatus for Developing Photographic Plates, of which the following, taken in connection with the accompanying drawings, is a full, clear, and exact description.

This invention relates to certain improvements in apparatus for developing photographic plates.

15 The main object is to provide a simple and easily portable apparatus by which the negative plate may be thoroughly developed, washed and fixed in daylight without liability of exposing any portion of such plate, thereby obviating the necessity for the usual 20 dark room and permitting the plates to be developed immediately following the exposure and in any locality where the photograph may be taken without leaving or 25 changing the position of the camera.

One of the specific objects is to provide means for transferring the plate holder from the camera to the developing apparatus without removing the exposed plate or 30 plates therefrom, so that when properly positioned on such apparatus, the negative plate may be deposited into the developer bath without liability of exposure, after 35 which the open side of the developer tray may be closed and the "dark frame" for the plate holder replaced by an auxiliary frame into which the negative plate may be withdrawn for successive transfer to the washing and fixing baths.

40 Another object is to provide the apparatus with means for receiving and supporting in compact space a plurality of developed plates for temporary storage and drying and capable of being transported 45 from place to place with the apparatus.

Other objects and uses relating to specific parts of the device will be brought out in the following description.

In the drawings—Figure 1 is a perspective view of a plate developing, washing and fixing apparatus embodying the various features of my invention ready for use, omitting the "dark frame." Figs. 2 and 3 are, respectively, an enlarged longitudinal

vertical sectional view taken on line 2—2, 55 and a transverse vertical sectional view taken on line 3—3, Fig. 1, except that the plate protecting frame for transferring the photographic plate from the developing tray to the washing and fixing trays is shown in 60 operative position upon the sliding carriage in registration with the developer tray. Fig. 4 is an enlarged face view of the upper portion of one end of the apparatus shown in Fig. 1, omitting the adjacent tank, the adjacent end of the handle strap being shown in section. Fig. 5 is a top plan, partly broken away, of a portion of the same apparatus, showing more particularly the sliding carriages and means for holding the plate carrier 70 in its elevated position. Fig. 6 is an enlarged longitudinal vertical sectional view, partly broken away, of the upper portion of the apparatus taken in the plane of line 6—6, Fig. 3. Fig. 7 is an enlarged longitudinal vertical sectional view, partly broken away, through the same apparatus taken in the plane of line 7—7, Fig. 3. Fig. 8 is a perspective view of what may be termed the "dark frame" for transferring the plate 80 holder from the camera to the developing apparatus, the plate holder being omitted. Figs. 9 and 10 are, respectively, a longitudinal vertical sectional view taken on line 9—9, 85 and a transverse vertical sectional view taken on line 10—10, Fig. 8, the plate holder being shown in operative position with the inner shutter removed to release the photographic plate to be developed. Fig. 11 is a detail sectional view of one side of the "dark 90 frame" and adjacent portion of the plate holder, showing the means for releasing the plate from the holder preparatory to depositing such plate into the developer tray. Fig. 12 is a perspective view of the plate 95 carrier for raising and lowering the plates into and out of the several trays. Fig. 13 is a side view of the movable carriage guide showing modifications in hinging and holding it in its normal position.

The plate holder as—A—is of the ordinary construction commonly used in photographic cameras for receiving and supporting the sensitized plates during exposure and is provided with the usual opaque partition—*a*—and one or more, in this instance two, sliding shutters—*a'*—which are guided in the frame of the holder to protect the

100

105

sensitized plates from exposure except when the holder is inserted in the camera, at which time the inner plate will be withdrawn to expose the sensitized surface of the plate to the action of light projected through the camera lens in the well known manner. The plate holder with the negative plate or plates therein is then withdrawn from the camera and placed in what may be termed a "dark frame" —1— which is recessed in one side for this purpose and is provided with suitable catches —2— hinged thereto for retaining the plate holder in the recess, the back of the "dark frame" being closed to exclude light from the negative plate when the inner shutter of the plate holder is withdrawn. One side of the plate holder is provided with the usual movable bar —b— spring pressed into engagement with the adjacent edge of the plate by one or more springs —b'— for retaining the photographic plate in the plate holder. In the adjacent side of the "dark frame" —1— is journaled a plate-releasing pin —3— movable endwise and having its inner end provided with a lateral offset —4— movable into and out of engagement with the bar —b— for withdrawing said bar from engagement with the adjacent edge of the photographic plate and releasing the latter, the outer end of the release pin —3— being provided with a handle —5— by which it may be turned and drawn outwardly when engaged with the bar —4— against the action of the springs —b'—, thereby permitting the photographic plate to be deposited into the recess as —6— of the "dark frame."

A shutter gate —7— is journaled along one edge in the back of the frame —1— below the lower edge of the plate holder —A—, as shown in Fig. 10, and extends from side to side of the bottom of the recess —6— for closing the same and excluding light, and also serves as a temporary support for the photographic plate which has been previously released from the plate holder into the recess —6—, said released plate being discharged from the plate holder by a slight shaking of the frame —1—.

When the photographic plate has been deposited into the recess —6— and upon its temporary support (gate —7—) the frame —1— is placed edgewise vertically upon a slide —8— which is guided on the upper side of a horizontally movable carriage —9— forming the top of the main case —10— of the apparatus. The slide —8— is provided with a lengthwise groove —11— in its upper side for receiving and temporarily retaining the lower edge of the "dark frame" —1— so as to cause the frame to move with the slide, which latter is also provided with an opening —12— registering with and running lengthwise of the groove —11— and

movable into and out of registration with a similar opening —13— in the carriage —9—, as shown more clearly in Figs. 3 and 5. When the slide —8— with the frame —1— mounted thereon is shifted to register its opening —12— with the opening —13—, the shutter —7— may be rocked downwardly in the direction indicated by the arrow in Fig. 10 by means of a handle —14— on the shutter spindle which extends through the frame to the outside thereof, as shown in Fig. 9, thus releasing the negative plate resting on the gate and permitting said plate to drop into the developer bath in an underlying tray —15— and on to a horizontal bar —16— of a vertically movable carrier —17—, as shown in Figs. 2 and 12. The shutter —7— is normally held in its closed position by a spring detent —14'— which engages the handle —14— and is secured to the adjacent side of the frame and may be released from its holding position by pressing its free end inwardly out of engagement with said handle to allow the shutter to rock downwardly under the weight of the plate resting thereon. After the negative plate has been deposited into the developer tray in the manner just described, the slide —8— with the frame —1— thereon is shifted rearwardly along suitable guides —18— in opposite ends of the carriage —9— until the opening —13— is effectively closed by the slide, whereupon the frame —1— is removed from the slide and laid aside and is replaced by another frame —19— having opposite plates —20— of red glass or equivalent material arranged in spaced relation for forming a chamber —21— to receive the negative plate which has been previously immersed in the developer bath in the tray —15—, the colored plates —20— being of such character and material as to render the photographic plate visible therethrough when held up to the light, and at the same time to prevent such light from having any effect upon the photographic matter on the negative plate.

Suitable means as a sliding catch —8'— is provided on the slide —8— for engaging the lower portions of either the "dark frame" —1— or transfer frame to hold said frames in the groove —11— against accidental displacement from the slide.

The frame —19— and its translucent colored plates —20— constitute what may be termed a transfer case for successively transferring the photographic plate as —B— from the developer tray to additional trays —23 and —24— containing, respectively, the washing fluid and fixing solution and is provided with an opening in its bottom in vertical registration with the chamber —21— and movable into and out of registration with the opening —13— in the carriage —9— so that by moving the carriage —9—

70

105

110

115

120

125

130

the chamber —21— and opening —13— may be brought into registration with the open upper ends of either one of the trays —15—, —23— and —24—. These trays are preferably arranged vertically side by side in close juxtaposition within the central portion of the case or housing —10—, leaving additional chambers —25— and —26— at the outer sides of the trays, the chamber —25— serving as a reservoir for receiving the fixed negative plates, while the chamber —26— serves to receive the transfer case when not in use or when transporting the entire apparatus from place to place.

15 The carrier —17— is provided with upright parallel rods —27— having their lower ends secured to opposite ends of the bar —16— and their upper ends extending through guide openings —28— in opposite ends of the carriage —9— just beyond the corresponding ends of the slide —8— so as not to interfere with the free action of said slide, and at the same time permitting the carrier to be moved back and forth with the carriage when raised to bring the bar —16— above the upper edges of the trays —15—, —23— and —24—, the upper ends of the rods —27— being connected by a handle —29— which is offset a sufficient distance to one side of the opening —13— to allow the "dark frame" —1— and transfer case to be readily inserted in the groove —11—.

It is now clear that after the transfer case has been properly placed upon the slide —8— and drawn back to register its opening —12— with the opening —13— which is then in registration with the open upper end of the developer tray —15—, the carrier —17— with the photographic plate thereon is moved up and down in the developer tray —15— and transfer case until the negative plate is fully developed, after which the carrier with the plate thereon may be raised a sufficient distance to bring the photographic plate wholly within the transfer case and opening —13— above the upper edge of the tray —15—, in which position the carrier may be locked by suitable catches —30— entering notches —31— in the upright rods —27—, as shown in Figs. 2 and 12, whereupon the carriage —9— with the transfer case containing the developed plate and also the carrier —17— may be shifted to bring the opening —13— in said carriage into registration with the next succeeding tray —23— containing the washing fluid, after which the catches —30— may be released and the carriage with the plate thereon lowered into the washing tray for thoroughly washing the plate by moving the carriage up and down. After the plate is washed in the manner described in the tray —23—, it is again raised by the carrier —17— into the transfer case and carriage —9—, which latter is again shifted to register its opening

—13— with the upper open end of the tray —24— containing the fixing bath, the carriage with the plate thereon being then lowered into the fixing tray and moved up and down until the negative is thoroughly fixed, whereupon the catch —8'— may be withdrawn and the transfer case removed and laid aside, after which the fixed plate may be raised by the carrier —17— through the opening —13— above the carriage a sufficient distance to allow it to be withdrawn by hand and placed in a suitable holder —32— in the chamber —25—.

The carriage —9— may be moved back and forth by hand, but for convenience of operation, I have secured to the lower face of its opposite ends near one side toothed racks —33— engaged by pinions —34— which are mounted upon a lengthwise shaft —35— having an external operating knob or wheel —36—, as shown more clearly in Figs. 3 and 6, said carriage being movable along and upon the upper edges of the case —10— and held in its operative position by angular guides —37—. One of the guides —37— is hinged at —38— to the adjacent end of the case so that it may be rocked out of engagement with the corresponding end of the carriage to permit the latter to be removed when it is desired to refill or remove the trays, it being understood that these trays are loosely mounted in the case to permit them to be withdrawn and refilled outside of the case if necessary, said movable guide being held in its normal position by one or more movable detents —39—, Fig. 4.

In order that the position of the slot or opening —12— in the slide —8— relatively to the opening —13— in the carriage —9— may be accurately determined, the upper faces of the opposite ends of the slide and adjacent portions of the carriage are provided with index marks —41—, which, when registered with each other, indicate that the slots or openings —12— and —13— are registered and when not so registered, as shown in Fig. 5, indicate that the opening —13— in the carriage is closed by the slide. The upper face of the opposite ends of the carriage is also provided with a series of graduations —42— movable successively into registration with an index mark —43— on the guides —37— to indicate the registration of the opening —13— with the upper ends of the several trays —15—, —23— and —24— so that the operator may accurately select the proper tray into which the photographic plate is to be inserted.

The bottom of the carrier —17— is provided with grooved seats —44— and upstanding spring arms —45— for retaining the photographic plate —B— in fixed relation thereto so that it may be readily raised and lowered into and out of the transfer case without liability of catching on the

edges of the openings in the carriage —9— and slide —8—.

The front and rear sides of the case —10— are preferably hinged at their lower edges at —46— to the bottom of said case to permit access to the inside of the compartments —25— and —26—, and are normally held in their closed positions by hooks —47— which are pivoted to the ends of the box and 10 engaged with suitable shoulders —48— on the adjacent ends of the sides.

The plate holder —32— in the compartment —25— is provided with upstanding arms or end-pieces —49— and —50— rising 15 from the bottom thereof and provided near their upper ends with clasps —51— in spaced relation for receiving the edges of the fixed photographic plates between them, one of the upright end-pieces as —50— being 20 adjustable lengthwise of the bottom —52—, and for this purpose its lower end is dovetailed and slidably fitted in a dovetailed groove —53—, thereby adapting the holder to plates of different sizes. The 25 other compartment —26— is of sufficient size to receive the transfer frame or case so that all the parts of the apparatus exclusive of the "dark frame" may be inclosed within or mounted upon the main case 30 —10—.

Another feature of my invention consists in providing the case with means for supporting one or more, in this instance two, cans or receptacles —55— and —56—, carrying, 35 respectively, a quantity of the developer and the fixing solution for replenishing the corresponding trays when desired, each can being provided with a pair of brackets —57— secured to the inner upright face 40 thereof and formed with key-hole slots —58— for engaging the heads of screws —59— or equivalent fastening means on the adjacent ends of the case —10— to lock the can thereto, and at the same time permit it 45 to be removed when necessary.

A pair of straps —60— and —61— are secured at one end to suitable loops —63— on opposite ends of the case, one of the sections —61— being provided with a buckle 50 for receiving the apertured end of the other section —60— to form a carrying strap by which the entire apparatus may be easily carried from place to place.

In Fig. 13, the movable angle guide for 55 the carriage is shown as supported by two hinges and is held in its normal position by a sliding detent —39'— guided thereon.

What I claim is:

1. In a developing apparatus, a tray for 60 developing liquid, a cover slidable across the top of the tray and having an opening for registration therewith, a slide on the cover having an opening movable into and out of registration with the opening in the 65 sliding cover, and means removably mount-

ed on the slide for transferring the plate to be developed from a plate holder through the registering openings and into the underlying tray.

2. In a developing apparatus, a case having 70 a slidable top provided with a lengthwise opening therein for receiving a photographic plate, a developer tray in the case having its upper end open and underlying the cover, a slotted slide on the cover, a plate-receiving case surrounding the slot in the slide and rising from the slide, and means guided in the cover separate from the slide for raising and lowering the plate in the tray and plate-receiving case. 75

3. In a developing apparatus, a case having 80 a slidable cover provided with a lengthwise opening for receiving a photographic plate, a tray within the case underlying said cover, and a plate carrier guided in 85 openings in the cover and movable in the tray for raising and lowering the plate and provided with a handle bar extending lengthwise of the opening at one side thereof. 90

4. In a developing apparatus for photographic plates, the combination with a case and a plurality of upright trays arranged side by side therein and open at the top, of a cover slidable across and upon the top 95 of the case and provided with a lengthwise opening registerable with the open tops of the trays one at a time, a slide movable across and upon the cover and provided with a lengthwise opening registerable with that 100 in the cover, a supporting frame for the plate holder having an open lower end resting upon and registering with the opening in the slide, and a shutter gate in the lower open end of the frame for temporarily supporting the photographic plate and excluding light therefrom, said gate being operable 105 at will to release the plate and allow it to enter the underlying tray. 110

5. In a developing apparatus for photographic plates, an upright tray open at the top and adapted to contain a developing solution and to receive a photographic plate, a superposed upright frame having an interior chamber adapted to receive a photographic plate, said chamber being open at the bottom and registerable with the open upper end of the tray to allow the photographic plate to be transferred from the frame to the tray and vice versa through the communicating passage, and a carrier for the plate movable in the tray, but wholly at the outside of the chamber in the superposed frame. 115

6. In a developing apparatus, the combination of a case, a plurality of plate-receiving trays within the case and open at the top, a carriage movable across the tops of the trays and provided with a lengthwise opening movable into and out of registra- 120 125 130

tion therewith, a plate-carrying frame covering said opening to permit the plate to pass therethrough, and means mounted on the carriage for raising and lowering the 5 plate in any one of the trays and transfer case registered therewith.

7. In a developing apparatus, a case containing a plurality of upright compartments for receiving, respectively, the developing 10 liquid, the washing liquid, and the fixing solution, a carriage movable across the tops of the trays and provided with an opening for successive registration therewith to receive a photographic plate, and a slide on the carriage movable across the opening therein and also provided with a lengthwise opening 15 for registration with the first named opening.

8. In a developing apparatus, a case containing a plurality of upright compartments for receiving, respectively, the developing liquid, the washing liquid, and the fixing solution, a carriage movable across the tops of the trays and provided with an opening 20 for successive registration therewith to receive a photographic plate, a slide on the carriage movable across the opening therein and also provided with a lengthwise opening 25 for registration with the first named opening, and a plate carrier mounted on the carriage and movable into and out of any one of said trays.

9. In a developing apparatus, the combination of a series of upright trays arranged 30 side by side and open at the top, a carriage movable transversely across the open tops of the trays and provided with a lengthwise slot 35 registrable therewith in sequence, and a vertically movable plate-carrier guided in 40 openings in said carriage at opposite ends of the slot and adapted to be registered with the upper open end of any one of the trays as the carriage is shifted for movement into and out of such tray.

45 10. In a developing apparatus, the combination of a series of upright trays arranged side by side and open at the top, a carriage movable transversely across the open tops of the trays and provided with a lengthwise slot 50 registrable therewith in sequence, a vertically movable plate-carrier guided in openings in said carriage at opposite ends of the slot and adapted to be registered with the upper open end of any one of the trays as

the carriage is shifted for movement into 55 and out of such tray, and coöperative means on the carriage and carrier, respectively, for locking the carrier in its uppermost position.

11. In a developing apparatus, a case having an opening in its top for receiving a photographic plate, a plurality of trays within the case and open at the top, said top being movable to register its opening with any one of the trays while covering the remaining 60 trays, and a shutter-slide mounted on the cover and movable across the opening therein to exclude light from the tray with which the opening may be registered.

12. In a developing apparatus, a case, a plurality of trays arranged side by side within 70 the case and open at the top, a cover for the case slidable across the upper ends of the trays and provided with a lengthwise opening movable into registration with any one of the trays and covering the remaining 75 trays, a shutter-slide mounted on the cover and provided with an opening movable into and out of registration with the opening therein, and a plate-receiving frame mounted on the slide and having an opening in its 80 bottom registering with that in the slide, said frame having translucent red colored sides.

13. In a developing apparatus of the character described, an upright tray open at the 85 top and adapted to receive a developing liquid and a photographic plate, a superposed cover having a lengthwise slot registrable with the open top of the tray to permit a plate to pass therethrough, an upright frame 90 above the cover having an interior chamber open at the bottom and registrable with said slot to receive a photographic plate and permit its passage therefrom through the slot and into the tray, and a shutter movable to 95 and from a position across said chamber near the lower open end thereof for temporarily supporting the plate and excluding light therefrom when closed and for permitting said plate to pass into the tray when the 100 shutter is opened.

In witness whereof I have hereunto set my hand this 4th day of February, 1915.

STEPHEN A. MISCHANSKY.
